UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

SEWING MACHINE.

Application filed January 9, 1922. Serial No. 527,932.

The invention relates to new and useful improvements in sewing machines, and more particularly to a sewing machine wherein the needle may be moved laterally for forming zigzag stitches.

An object of the invention is to provide a sewing machine with means for vibrating the needle laterally to form zigzag stitches, and devices which are operated from the means for shifting the needle laterally for shifting the working position of the looper to correspond with the lateral shifting of the needle.

A further object of the invention is to provide a sewing machine with means for shifting the working position of the needle and the looper, and with means for suspending the shifting movements of said needle and looper whereby straight-away or zigzag stitches may be produced at will.

A further object of the invention is to provide a sewing machine of the above type wherein the lateral shifting movements of the needle and looper are suspended by disconnecting said needle and looper from the shifting means.

A still further object of the invention is to provide a machine of the above type with means for holding said needle and looper from shifting laterally when disconnected from the shifting means.

These and other objects will in part be obvious and will in part be hereinafter more fully disclosed.

In the drawings which show by way of illustration one embodiment of the invention—

Figure 1 is a view partly in front elevation and partly in longitudinal section showing a sewing machine embodying my improvements;

Fig. 2 is a view of the machine from the rear;

Fig. 3 is a sectional view on the line 3—3 of Fig. 2;

Fig. 4 is a sectional view on the line 4—4 of Fig. 2, certain of the parts beneath the work support being shown in dotted lines;

Fig. 5 is a sectional view on the line 5—5 of Fig. 4;

Fig. 6 is a perspective view of the means for shifting laterally the working position of the looper;

Fig. 7 is a sectional view on the line 7—7 of Fig. 8;

Fig. 8 is a view from the front of the machine showing a portion of the means for shifting the looper laterally, the looper being positioned for cooperation with the needle and at the left-hand end of its zigzag stroke, and

Fig. 9 is a similar view but showing the looper positioned for cooperation with the needle when at the right-hand end of its zigzag stroke.

65

In carrying out the invention, I have provided a needle which is mounted so that the same may be moved laterally for producing zigzag stitches. This is accomplished by mounting the needle in the needle bar which reciprocates in a needle bar gate, and the gate is capable of being oscillated by means which may be connected to or disconnected from a constantly vibrating arm. Cooperating with the needle beneath the work support 70 is a threaded looper which is preferably set so as to move in a plane at right angles to the line of feed. This threaded looper is oscillated about a fixed center. The oscillating mechanism for the looper includes devices 75 which may be shifted so as to change the working position of the looper to correspond with the lateral shifted position of the needle so that the needle and the looper in both of its extreme lateral positions are timed 80 whereby the looper crosses the needle on the same line and thus with certainty enters a needle thread loop. In other words, the looper will take the needle thread loop at exactly the same height at each end of the 85 zigzag position, thus reducing the liability of the skipping of stitches.

The means for shifting the working position of the needle and the looper laterally may be adjusted for varying the length of 90 the zigzag stitches. The needle and looper may also be disconnected from the lateral shifting means for producing straight-away stitching and devices are provided for holding the needle and the looper from shifting laterally while straight-away stitching is being produced.

Referring more in detail to the drawings, I have shown the invention as applied to a sewing machine for forming straight-away and zigzag stitches of the type illustrated in the Patent Number 1,255,802, granted D. S. Seymour, February 5, 1918. Said machine includes a needle 1 which is carried by a needle bar 2 which in turn is mounted to 105 110

reciprocate in a swinging gate 3. The needle bar is reciprocated by a needle lever 4 connected by a link 5 to the needle bar. Said needle lever is oscillated by an eccentric 6 strap 6 which cooperates with an eccentric 7 on the main shaft 8. The needle bar gate 3 as shown in Fig. 5 is pivoted at 9 and is provided with an arm 10 by which the needle bar gate may be swung about its pivotal support. The arm 10 is connected by a link 11 to a depending arm 12 carried by a shaft 13 mounted in rear of the overhanging arm of the machine 4 and journaled in bearing brackets carried by said overhanging arm. 10

Mounted on the shaft 13 is a second depending arm 14. Loosely mounted on the shaft 13 is an arm 15. Said arm 15 is connected to a link 16 and the link in turn is connected to a ball stud mounted for adjustment in a slotted forked lever 17. This slotted forked lever 17 is pivotally supported at its upper end by the overhanging arm. Said forked lever at its lower end straddles a cam or eccentric carried by a stub shaft which is rotated by a gear wheel 18. Said gear wheel 18 is in turn rotated by a gear wheel 19 on the main shaft 8. The arms 14 and 15 are adapted to be connected together by means of a bar 20. Said bar 20 projects laterally from a collar 21 fixed to a rod 22 which slides freely in a sleeve portion of the arm 14. Said rod is normally forced downwardly so as to disconnect the arms. The rod 22 may be raised so as to connect the arms by means of a support 23 on which a roller 24 journaled in bearings at the lower end of the rod 22 bears. When the support 23 is raised to the position shown in Fig. 2, the rod 22 is raised so that the bar 20 connects the arm 14 with the arm 15. When the support 23 is lowered, then a suitable spring forces the rod 22 downwardly and disconnects the arm 14 from the arm 15. The arm 15 is continuously vibrated by means of the link 16 and the forked lever 17 so that when the arm 14 is connected to the arm 15, the shaft 13 will be oscillated and this in turn will impart vibrations to the needle bar, thus causing the needle to form zigzag stitches. When, however, these arms are disconnected one from the other, then the oscillations of the arm 14 cease and the needle will form straight-away stitching. When the parts are disconnected, a V-shaped projection 25 on the lower face of the bar 20 engages a similar V-shaped recess in the bracket 26 and this recess is so positioned relative to the projection that the needle will be positioned at the extreme outer end of the zigzag stroke, or at the left-hand end of the zigzag stroke as viewed from the front of the machine. In other words, the needle when disconnected from its vibrating mechanism forms a straight line of stitching, and when connected to the vibrating mechanism forms

zigzag stitching which extends to the right of the straight-away stitching as viewed in Fig. 1. The support 23 is raised by means of a lever 27 which is pivoted at 28 and is provided with a forked arm engaging a screw 29 threaded into the standard 30 on which the support 23 is mounted. A spring 31 is mounted on the standard 30 and bears against a collar 32 thereon and normally operates to move the support 23 downwardly depressing the inner end of the lever 27. A swinging lever 33 pivoted at 34 may have its inner end 35 swung beneath the inner end of the lever 27 and thus hold the support 23 raised and the two arms 14 and 15 locked together. When it is desired to do straight-away stitching, the locking lever 33 is thrown to one side and this releases the lever 27. The lever 27 may be connected to a treadle and the operator can control said lever through the treadle so as to make zig-zag or straight-away stitches at will. The above parts are all substantially the same as those shown in the Seymour patent and it is not thought that further description is necessary. The present invention is directed particularly to means for shifting laterally the working position of the looper so as to correspond to the lateral shifting of the needle, which looper shifting means is so constructed that whatever the lateral adjustment of the needle may be, the looper will be properly positioned for cooperating with the needle, and whenever said needle is disconnected from its shifting means for straight-away stitching, the looper will be held against any lateral shifting of the working position thereof. Cooperating with the needle beneath the work support is a threaded looper 36. Said threaded looper 36 is mounted on a looper carrier 37. Said looper carrier 37 is pivoted at 38 to a looper support 39. Said looper support 39 is provided with a forked arm 40 which cooperates with an eccentric on the main shaft 8 and operates to impart a lateral or needle avoiding movement to the looper. Said looper is mounted so as to oscillate in a plane at right angles to the line of feed and the oscillations are imparted to the looper by means of a link 41. Said link 41 is pivoted at its right-hand end to a ball stud 42 carried by a lever 43 fulcrumed on a pin 44 intermediate its ends. The pin 44 is threaded into an arm 45 which is pivotally supported by the fulcrum pin 46 fixed to the frame. The arm 45 is connected at its upper end by means of a link 47 to the needle lever extension 48. As the needle lever vibrates, it will rock the arm 45 and this will cause the fulcrum pin 46 for the lever 43 to move bodily back and forth. The lever 43 is connected by a pin 49 to a link 50. The link 50 is pivotally connected to an arm 51 fixed to a shaft 52 mounted in bearings 53 and 54 carried by 70

suitable brackets mounted on the bed plate of the machine. The shaft 52 carries a second arm 55 which is provided with a radial slot 56 in which a ball stud 57 is capable of 5 being adjusted toward and from the center of the shaft 52. A link 58 is pivotally connected at its lower end to the ball stud 57. Said link 58 at its upper end is pivoted to a ball stud 59 carried by an arm 60 which is 10 clamped to the shaft 13.

It will thus be seen that as the shaft 13 is oscillated, the link 58 will be moved endwise and this will impart oscillations to the shaft 52 and through the arms 51 and 50 im- 15 part oscillations to the pin 49 at the lower end of the lever 43. As the needle bar is shifted from one lateral position to the other, the pin 49 will be correspondingly shifted from one set position to another.

20 Let us assume for a moment that the arm 45 is a fixed arm. It will readily be seen that as the pin 49 is shifted it will turn the lever 43 so as to move the looper from one position to another on its pivotal support 38.

25 So it is that during the operation of the machine, the looper receives its normal oscillations through the link 41 which causes the looper to move into the needle thread loop and out of the needle thread loop. The 30 shifting of the pin 49 will, however, change the working position, that is, the oscillating position of the looper, and always cause said looper to cross the needle at the same height or point, regardless of whether the needle 35 is at one end or the other end of its lateral vibration. Inasmuch as the looper always crosses the needle at the same height, there is no liability of skipping stitches, and the needle may be given a relatively long lateral

40 vibration for making relatively long zigzag stitches without any liability of skipping stitches. By adjusting the ball stud 57 in the slot 56, the lateral throw of the working position of the looper may be varied and 45 so a proper timing may be obtained between the looper and the needle. The amount of vibration imparted to the needle may be varied by adjusting the connection of the link 16 to the forked lever 17. This adjustment will vary the amount of oscillation im- 50 parted to the shaft 13. Inasmuch as the working position of the looper is shifted through the connection with the arm 60 carried by the shaft 13, it will readily be seen

55 that the working position of the looper will be shifted a greater extent when the needle is shifted a greater extent so that no matter what may be the length of the lateral throw of the needle, the shifting of the working 60 position of the looper will always correspond to said lateral throw of the needle.

Then again, when the machine is set for straight-away stitching, the shaft 13 is disconnected from the arm 15 which continues 65 to vibrate, and when disconnected from said

arm, it is locked or held in a fixed position by means of the V-shaped projection 25 en- 70 gaging the corresponding V-shaped recess in the bracket 26. This locks the shaft 13 against any oscillation. Inasmuch as the working position of the looper is shifted laterally by the oscillation of the shaft 13, when said shaft is locked against movement to hold the needle from shifting laterally while straight-away stitching, the looper will 75 likewise be locked so that its working position cannot shift.

It is obvious that minor changes in the details of construction and the arrangement of the parts may be made without departing from the spirit of the invention as set forth in the appended claims. 80

Having thus described the invention, what I claim as new and desire to secure by Letters Patent, is—

85 1. A sewing machine for forming both straight away and zigzag stitches, including in combination a feeding mechanism, a needle, a looper cooperating therewith having its loop taking and loop shedding move- 90 ments in a line substantially at right angles to the line of feed, an actuating device, and means connected thereto for shifting said needle and looper back and forth across the line of feed without disturbing their coop- 95 erative relation for forming zigzag stitches, and means under the control of the operator for disconnecting the shifting means from its actuating device for suspending the opera- 100 tions of the needle and looper shifting means. 105

2. A sewing machine for forming both straight away and zigzag stitches, including in combination a feeding mechanism, a needle, a looper cooperating therewith having its loop taking and loop shedding move- 110 ments in a line substantially at right angles to the line of feed, an actuating device, and means connected thereto for shifting said needle and looper back and forth across the line of feed without disturbing their coop- 115 erative relation for forming zigzag stitches, means under the control of the operator for disconnecting the shifting means from its actuating device for suspending the opera- 120 tions of the needle and looper shifting means, and means adapted to be connected to the needle and looper shifting means for locking the same in a fixed position when disconnected from said actuating means.

3. A sewing machine including in combi- 125 nation, a needle, a needle bar, a needle gate in which said needle bar reciprocates, a shaft connected to said needle gate, an arm carried by said shaft, a continuously vibrating member, and means for connecting the same to the said arm for oscillating the gate and for disconnecting the same from said arm for suspending the vibrations of the gate, a looper, means for oscillating said looper for causing the same to cooperate with the 130

needle, and devices connected with said shaft for varying the working position of the looper to correspond with the lateral shifted positions of the needle.

5. A sewing machine including in combination, a needle, a needle bar, a needle gate in which said needle bar reciprocates, a shaft connected to said needle gate, an arm carried by said shaft, continuously vibrating means 10 adapted to be connected to said arm for oscillating the gate, a looper, means for oscillating said looper for causing the same to cooperate with the needle, devices connected with said shaft for varying the working position 15 of the looper to correspond with the lateral shifted positions of the needle, manually controlled devices for connecting said continuously vibrating member to said arm or disconnecting the same therefrom for 20 forming zigzag or straight-away stitches at will.

5. A sewing machine including in combination, a needle, a needle bar, a needle gate in which said needle bar reciprocates, a shaft 25 connected to said needle gate, an arm carried by said shaft, continuously vibrating means adapted to be connected to said arm for oscillating the gate, a looper, means for oscillating said looper for causing the same to cooperate with the needle, devices connected with 30 said shaft for varying the working position of the looper to correspond with the lateral shifted positions of the needle, manually controlled devices for connecting said continuously vibrating member to said arm or disconnecting the same therefrom for 35 forming zigzag or straight-away stitches at will, and means adapted to be connected to said arm when said arm is disconnected from the continuously vibrating member for preventing 40 the needle bar and looper from shifting laterally while forming straight-away stitches.

6. A sewing machine including in combination, a needle, means for vibrating the 45 needle laterally including an oscillated member, manually controlled devices adapted to be connected thereto for shifting said needle laterally, a thread carrying looper cooperating with said needle, a link connected to 50 said thread carrying looper for oscillating the same, a lever to which said link is pivoted, means connected to the lever for vibrating the same for oscillating the looper, a shiftable fulcrum for said lever, and means 55 connected to said oscillated member for vibrating the needle laterally for shifting the fulcrum of said lever whereby the working position of the looper is shifted to correspond to the lateral vibrations of the needle.

60. 7. A sewing machine including in combination, a needle, means for vibrating said needle laterally including an oscillated member, a thread carrying looper cooperating with said needle, a link connected to said 65 looper for operating the same, a lever piv-

oted at its upper end to said link, means connected to said lever intermediate its ends for oscillating the same, a shiftable fulcrum at the lower end of said lever, a cross shaft, said cross shaft being connected to said shiftable fulcrum for shifting the same, and a link connecting said cross shaft with said oscillated member whereby the working position of the looper is shifted laterally to correspond to the lateral shifted positions of the needle. 70 75

8. A sewing machine including in combination, a needle, means for vibrating said needle laterally including an oscillated member, a thread carrying looper cooperating with said needle, a link connected to said looper for operating the same, a lever pivoted at its upper end to said link, means connected to said lever intermediate its ends for oscillating the same, a shiftable fulcrum at 80 the lower end of said lever, a cross shaft, said cross shaft being connected to said shiftable fulcrum for shifting the same, and a link connecting said cross shaft with said oscillated member whereby the working position of the looper is shifted laterally to correspond to the lateral shifted positions of the needle, said connection between the cross shaft and the oscillated member being 85 adjustable whereby said looper may be properly timed to cooperate with the needle. 90 95

9. In a sewing machine for forming both straight away and zigzag stitches, the combination of a needle, a looper cooperating therewith, means for shifting said needle and looper back and forth in a direction at right angles to the line of feed without disturbing their cooperative relation for forming stitches, devices for actuating said shifting means, and means for connecting and disconnecting said actuating means to said shifting means without stopping the machine. 100 105

10. In a sewing machine for forming both straight away and zigzag stitches, the combination of a needle, a looper cooperating therewith, means for shifting said needle and looper back and forth in a direction at right angles to the line of feed without disturbing their cooperative relation for forming stitches, devices for actuating said shifting means, means for connecting and disconnecting said actuating means to said shifting means without stopping the machine, and means for automatically locking said shifting means when said actuating means therefor is disconnected so that said needle will be held to reciprocate in a fixed position during straight away stitching. 110 115 120

11. A sewing machine for forming straight away and zigzag stitches including a feeding mechanism, a needle, a threaded looper, means for supporting said looper whereby the same may be oscillated in a plane substantially at right angles to the line of feed, 125 130

- means for oscillating the looper, means for giving said looper a needle avoiding movement, means for shifting the needle in a direction at right angles to the line of feed and 5 for shifting the working position of the looper so that their cooperative relation for forming stitches is not disturbed, and means under the control of the operator for simultaneously suspending the needle shifting 10 means and the looper shifting means.
12. In a sewing machine for forming both straight away and zigzag stitches, the combination of a needle, a feeding mechanism, a looper mounted for oscillation in a plane 15 substantially at right angles to the line of feed, means for shifting the needle in a direction at right angles to the line of feed, means for giving said looper a needle avoiding movement, means for shifting the oscillating position of the looper when the needle 20 is shifted, so that the cooperative relation of the needle and looper for forming stitches is not disturbed, devices for actuating said shifting means, and means for connecting and disconnecting said actuating means to 65 the shifting means without stopping the machine.
13. A sewing machine for forming straight away and zigzag stitches including a feeding mechanism, a needle, means for vibrating the 70 needle laterally substantially at right angles to the line of feed, a threaded looper, means for giving the looper a needle avoiding movement and for oscillating the looper on its support in a plane substantially at right 75 angles to the line of feed, said means for oscillating the looper including devices for causing said looper to move in a predetermined path when making straight away stitches and for changing the character of 80 the path when the machine is making zigzag stitches whereby the cooperative relation between the needle and looper remains unchanged.

In testimony whereof, I affix my signature.
JAMES R. MOFFATT.
